UNITED STATES PATENT OFFICE.

OLIVER WINFORD CROOKS AND ELMER HARRY CROOKS, OF BIG CREEK, CALIFORNIA.

DUMPING MINE CAR.

Application filed December 22, 1921. Serial No. 524,186.

To all whom it may concern:

Be it known that we, OLIVER WINFORD CROOKS and ELMER HARRY CROOKS, citizens of the United States, residing at Big Creek, 5 in the county of Fresno and State of California, have invented new and useful Improvements in Dumping Mine Cars, of which the following is a specification.

Our invention relates generally to vehicles 10 having bodies capable of being operated to effect dumping of their contents, and more particularly to dumping mine cars.

The purpose of our invention is the provision of a mine car having a swingingly supported body mounted to normally occupy a position in which the contents of the body are retained therein, and which is movable to effect the dumping of the contents to either side of the car, our invention 20 including mechanism for moving the body to dumping position which can be operated independently or in conjunction with the mechanism of similarly constructed cars.

We will describe one form of dumping 25 car embodying our invention and will then point out the novel features thereof in claims.

In the accompanying drawings—

Figure 1 is a view showing in side elevation one form of car embodying our invention.

Figure 2 is a vertical sectional view taken on line 2—2 of Figure 1.

Referring specifically to the drawings in 35 which similar reference characters refer to similar parts, our invention in its present embodiment comprises a chassis designated as C and supported for rolling movement by wheels W. Upstanding from the chassis C 40 at points adjacent the opposite ends thereof are standards D and D' formed with openings adapted to rotatively receive stub axles 15 formed on the opposite ends of a bucket or body B.

As clearly shown in Figure 2, the body B 45 includes end walls 16 of substantially triangular formation which are rigidly connected by side and bottom walls 17 arranged in the form of a V to provide reversely inclined 50 surfaces to facilitate the dumping of the contents to either side of the car.

Medially of the ends of the body B a master gear G is formed, and this gear is of substantially semi-circular formation so 55 as to maintain meshing relation with respect to an actuating pinion P irrespective of the

position of the body. The pinion P is mounted on a squared portion 18 of a drive shaft S so as to be rotatable therewith while at the same time being capable of movement 60 longitudinally to engage or disengage the master gear G. To effect this movement of the pinion P a sleeve 19 is slidably fitted upon the shaft portion 18 and provided with a squared bore so as to be rotatable with 65 the pinion and shaft. The sleeve 19 is recessed to accommodate a fork 20 fixed to one end of rod 21 slidably mounted in the standard D' and pivotally connected at its opposite end to the lower end of actuating 70 lever 22. The lever 22 is fulcrumed between and upon ears 23 at the point indicated at 24 with its upper end provided with a handle 25 adapted to be gripped in actuating the lever.

As clearly shown in Figure 1 the shaft S is rotatably mounted in end bearings 26 and an intermediate bearing 27 all supported on chassis C. One end of the shaft S is shown as provided with a crank 28, and its 80 opposite end with a universal joint 29 to permit of its connection with the corresponding shaft of a similarly constructed mine car so that by actuation of the crank 28 rotation of the shafts of both cars is effected so that the shafts of both cars will be operated simultaneously and irrespective of the relative position of such shafts.

In operation, the body B because of its 90 formation normally occupies, under the action of gravity, the position shown in Figure 2 so as to retain the contents of the body therein. With the pinion P in mesh with the master gear G, it will be clear that by rotation of the shaft S a corresponding 95 movement is imparted to the pinion to effect rotation of the body B to cause a dumping of its contents. The contents can be dumped to either side of the car depending upon in which direction the shaft S is rotated, that is to say, when the shaft is rotated in a clockwise direction as when viewed in Figure 2 the body will be rotated to the right thereby dumping the contents 100 to the left side of the car.

In a train of mine cars so constructed and having their shafts S operatively connected to each other through the universal joints 29, it will be clear that when sufficient power is applied to the crank 28 a simultaneous 110 operation of all the shafts can be effected. Assuming that all of the pinions P are in

mesh with their corresponding gears G a dumping of the contents of all of the cars is readily effected. By virtue of the mechanism for shifting the pinion P, the bodies B of any of the cars of the train can be operatively connected or disconnected to or from the shafts S so that only the desired cars will be dumped.

Although we have herein shown and described only one form of dumping mine car embodying our invention it is to be understood that various changes and modifications may be made herein without departing from the spirit of the invention and the spirit and scope of the appended claims.

What we claim is:

1. In combination, a dumping mine car including a movable body, mechanical means for moving the body to effect a dumping of its contents, means on the car for positively actuating the first means and mechanical means adapted to operatively connect said means with similar means of another car body to effect simultaneous actuation of the second car body.

2. A dumping mine car comprising a chassis, standards formed on the chassis, a

body swingingly sustained on the standards and of V-form in cross section, a master gear fixed to the body, a shaft journaled on the chassis, a pinion mounted on the shaft and movable to engage or disengage said gear and manually operable means for moving said pinion.

3. A dumping mine car comprising a chassis, a body swingingly supported on the chassis, means for moving the body to effect the dumping of its contents, said means including a shaft, and means at one end of the shaft adapted for operatively connecting the same to a similar shaft.

4. A dumping mine car comprising a chassis, standards formed on the chassis, a body swingingly sustained on the standards, a master gear fixed to the body, a shaft journaled on the chassis, a pinion mounted on the shaft and movable to engage and disengage said gear, and means for moving said pinion.

In testimony whereof we have signed our names to this specification.

OLIVER WINFORD CROOKS.
ELMER HARRY CROOKS.
